PRESSURE TRANSMITTING DEVICE

Charles John Schwab, Fox River Grove, Ill. (½ Brock Equipment Company, 4525 N. Ravenswood Ave., Chicago 40, Ill.)

Filed Apr. 30, 1957, Ser. No. 656,067

7 Claims. (Cl. 60—54.6)

This invention relates to a pressure transmitting device and more particularly to such a device for transmitting pressure from a source of operating fluid to a fluid operated element without a fluid connection therebetween.

An object of this invention is to provide a new and improved device for transmitting pressure from a source of operating fluid to a fluid operated element without any fluid connection therebetween.

Another object of the invention is to provide a pressure transmitting device for transmitting pressure from a source of operating fluid to a fluid operated element in which there is no fluid connection between said source and said element and which may be of substantial length and has a major part of its length formed of electrically nonconducting material to permit use of the device on and in the area of energized electrical conductors.

A further object of the invention is to provide a device for transmitting fluid pressure from a source of operating fluid to a fluid operated element having a first means movable in response to the pressure of the operating fluid exerted thereon, a second means movable to exert pressure on another body of fluid communicating with the fluid operated element, and means connecting said first and second means for movement together to transmit force from said first means to said second means.

An additional object of the invention is to provide a hydraulic hot stick for transmitting pressure from a source of fluid to a fluid operated tool or the like comprising, means adapted for connection to the source of fluid including a cylinder having a piston movable therein, means adapted to receive a tool or the like and have fluid communication therewith including a cylinder and a piston movable therein, electrically nonconducting means for connecting said cylinders in fixed relation to each other including an elongated hollow tube connected between the cylinders, electrically nonconducting means for connecting said pistons together for simultaneous movement including an elongated rod extending through and slidably confined in said tube and connected between said pistons, and fluid seal means for sealing the cylinders from the hollow tube.

The objects of the invention generally set forth together with other ancillary advantages are attained by the construction and arrangement shown by way of illustration in the accompanying drawing, in which:

Fig. 1 is a view in elevation of the pressure transmitting device, with a compression tool or the like mounted at one end thereof, and a source of operating fluid connected to the other end thereof;

Fig. 2 is a plan section of the pressure transmitting device taken generally along the line 2—2 in Fig. 1, with the tool and source of operating fluid detached from the device;

Fig. 3 is a vertical section taken generally along the line 3—3 in Fig. 2; and

Fig. 4 is a plan section taken along the line 4—4 in Fig. 2.

The pressure transmitting device is indicated generally

2

at A. As shown in Fig. 1, for the purposes of illustration the device A may have a hydraulic compression tool 1 attached at one end thereof; and a source 2 of operating fluid connected to the other end thereof. The source 2 5 may connect with a pump or to a line providing a source of operating fluid under pressure.

The pressure transmitting device A has means adapted for connection to the source 2 of operating fluid comprising a metal cylinder 3 of aluminum or the like in which a piston 4 is slidably mounted and having an inlet passage 5 for the operating fluid. An O-ring 6 surrounds the piston so as to form a seal with an inner wall of the cylinder 3.

The pressure transmitting device A has means adapted 15 to receive a tool or the like and have fluid communication therewith comprising a second metal cylinder 10 of aluminum or the like in which a piston 11 is movably mounted and having an outlet passage 12 from an end of the cylinder. An O-ring 13 surrounds the piston 11 20 to provide a seal with an inner wall of the cylinder 10.

Means for connecting said cylinders together in fixed 25 relation to each other comprises an elongated, hollow connection in the form of a tube 15 secured at its opposite ends to metal ferrules 16 and 17, respectively, by suitable 30 connections such as the threaded connections 18 and 19. The ferrules 16 and 17 threadably connect with open 35 ends of the cylinders 3 and 10, the ferrule 16 having a threaded connection 20 with the cylinder 10, and the ferrule 17 having a threaded connection 21 with the cylinder 3.

Means are provided for connecting the pistons 4 and 11 together for simultaneous movement including an 40 elongated connecting member in the form of a rod 25 extending through and slidably confined in the hollow tube 15. The rod 25 passes through a pair of bores 26 and 27 in the ferrules 16 and 17, respectively, and into the cylinders 3 and 10. The bores 26 and 27 each has an O-ring 28 and 29, surrounding the rod 25, respectively, 45 for sealing the cylinders 3 and 10 from fluid communication with the hollow tube 15.

When oil is pumped under pressure into the first cylinder 3, the piston 4 will advance toward the left, as viewed in Fig. 2, which, through the connecting rod 25, will advance the piston 11 toward the left; and the left-hand end of cylinder 10 having been previously filled with fluid, the fluid will be forced out of the second cylinder 10 to the hydraulically operated member such as a piston in the tool 1. As shown in the drawing, the cylinders 3 and 10 and the pistons 4 and 11 are of the same size so 50 that the outlet pressure from the second cylinder 10 will be the same as the inlet pressure into the first cylinder 3. The piston 4 defines a fluid chamber in the cylinder 3 extending to the inlet passage 5. The piston 11 defines a fluid chamber in the cylinder 10 extending to the outlet 55 passage 12.

Although a tool 1 is shown in association with the pressure transmitting device A, it is readily apparent that this device may be used to operate any member responsive to hydraulic pressure. The device may be formed 60 from parts made of metal or other material capable of withstanding the forces exerted, particularly the tension forces in the hollow tube 15, and the compression forces in the connecting rod 25.

The device A is readily usable as a hydraulic hot stick, 65 in which case the hollow tube 15 and connecting rod 25 would be formed of electrically nonconducting material. The tube 15 has a relatively thick wall and may be suitably formed of woven glass fiber laminations bonded with a plastic resin such as a phenolic formaldehyde, polyester, or epoxy resin. The connecting rod 25 may be suitably 70 formed from a plastic resin as, for example, an epoxy, polyester, or phenolic formaldehyde resin with glass fiber

rovings for reinforcement. In operating compression tools, oil pressures of up to 10,000 p.s.i. may be encountered, and it would be necessary to have metal reinforcements in any hose designed to withstand this pressure with the result that such a hose would be a conductor. This problem is overcome in the disclosed device, and avoids any fluid connection through the major part of the length of the device. The pressure transmitting device transmits hydraulic pressure from a source of power to the operating device without any metallic or fluid contact therebetween.

A spring 30 surrounds one end of the connecting rod 25 and engages between the ferrule 17 and the piston 4 to function as a return spring for the pistons 4 and 11. The connecting rod 25 is secured at each of its ends to the adjacent piston by a ball and socket joint to permit the piston to freely slide in its cylinder in the event slight bending should occur in the rod 25. This ball and socket joint is formed, as shown in Fig. 4, by providing a slightly concave surface 31 in the piston and rounding an end 32 of the connecting rod 25. A split collar 33 is fitted in an annular groove 34 in an end of the connecting rod 25, and a threaded ring 35 for retaining the split collar is threaded into the piston, as shown at 36.

In order to retain fluid in the cylinders 3 and 10, one part of a two-part high-pressure quick coupler may be associated with the inlet passage 5 and the outlet passage 12. A suitable coupler is that offered by Pioneer Hydraulics Co., Inc., as its Item No. 3000 in which a complete coupler has a male half and a female half with a ball mounted in each half, so that, when the source 2 or device such as tool 1 is attached, the ball in the component of the coupler carried thereby will engage and move the ball in the component secured to the pressure transmitting device A to place the parts in fluid communication.

I claim:

1. A hydraulic hot stick for transmitting hydraulic pressure from a source of operating fluid to a fluid operated tool or the like, comprising, in combination, means adapted for connection to the source of operating fluid including a metal cylinder having an inlet passage at an end thereof for operating fluid and a cylindrical piston movably mounted in the cylinder forming a fluid chamber in the cylinder between the piston and the inlet passage, means adapted to receive a tool and have fluid communication therewith for exerting fluid pressure on the tool including a metal cylinder having a fluid outlet passage at an end thereof and a cylindrical piston movably mounted in the cylinder forming a fluid chamber in the cylinder between the piston and the outlet passage, said cylinders and said pistons being of substantially the same diameter, electrically nonconducting means for connecting said cylinders in fixed spaced end-to-end relation to each other including an elongated hollow tube of glass fiber reinforced plastic resin, a metal ferrule threadably connecting each end of the tube one to each of the other ends of said cylinders, electrically nonconducting means for connecting said pistons together for simultaneous movement including an elongated rod of glass fiber reinforced plastic resin slidably confined in said tube and having its ends extending through the other ends of the cylinders and secured one to each of the pistons by a ball and socket type joint, and fluid sealing rings in said ferrules in engagement with the rod for sealing the cylinders from the hollow tube.

2. A hydraulic hot stick as defined in claim 1, and having a return spring mounted in the cylinder adapted for connection to the source of operating fluid, said spring being in engagement with the piston therein for urging the piston toward said inlet passage.

3. A portable hydraulic hot stick for transmitting pressure from a source of operating fluid to a fluid operated device carried on the hot stick comprising, in combina-

tion, means adapted for connection to the source of operating fluid including a cylinder having an inlet adjacent an end thereof for operating fluid and a piston movably mounted in the cylinder, means adapted to have fluid communication with said device for exerting fluid pressure on the device including a cylinder having a fluid outlet adjacent an end thereof and a piston movably mounted in the cylinder, electrically nonconducting means for connecting said cylinders in fixed spaced end-to-end relation to each other including an elongated hollow tube having a length many times greater than its diameter and having its ends secured one to each of the cylinders, electrically nonconducting means for connecting said pistons together for simultaneous movement including a rod extending slidably through said tube and having its ends extending within the cylinders and secured one to each of the pistons, and fluid sealing means for sealing the cylinders from the hollow tube.

4. A hydraulic hot stick as defined in claim 3, wherein each end of the rod and the associated piston are shaped to provide a ball and socket connection to permit slight pivoting of the rod relative to the piston and prevent relative longitudinal movement therebetween, and a return spring mounted in one of the cylinders and engageable with the piston therein for urging the piston in a direction opposing the force of the operating fluid.

5. A portable device for transmitting pressure from a source of operating fluid to a fluid operated tool element comprising, a first cylinder having a piston therein movable in response to the pressure of the operating fluid exerted thereon, a second cylinder having a piston therein for exerting pressure on another body of fluid for operating the tool element, a hollow tube formed of electrically nonconducting material connecting the cylinders together in fixed spaced end-to-end relation to each other, and an elongated rod formed of electrically nonconducting material slidably confined throughout the length of said tube and connecting said pistons together for simultaneous movement to transmit pressure from the operating fluid to said other body of fluid.

6. A portable hot stick device for transmitting pressure from a source of operating fluid to a fluid operated element carried on the device comprising, a first cylinder having a piston therein movable in response to the pressure of the operating fluid exerted thereon, a second cylinder having a piston therein for exerting pressure on another body of fluid, an elongated electrically nonconducting member connecting said pistons together for simultaneous movement to transmit force from the operating fluid to said other body of fluid, and elongated electrically nonconducting means connecting the cylinders together in fixed relation to each other and slidably confining said elongated member.

7. A portable hydraulic hot stick for transmitting the force of hydraulic pressure a substantial distance, in lieu of a hose, from a source of operating fluid under pressure to a fluid operable tool, comprising, in combination, means adapted for connection to a source of operating fluid including a cylinder having an inlet passage adjacent one end thereof for operating fluid and a piston slidable into the cylinder forming a fluid chamber in the cylinder between the piston and the inlet passage, means adapted to carry a tool and have fluid communication therewith for exerting fluid pressure on the tool including a cylinder having a fluid outlet passage at one end thereof and a piston slidable in the cylinder forming a fluid chamber in the cylinder between the piston and the outlet passage, means connecting the cylinders in fixed spaced end-to-end relationship to each other including a long slender electrically nonconducting tube and means fixedly connecting opposite ends of the tube to the other cylinder ends respectively, said tube having a length substantially greater than the length of the cylinders and many times greater than the diameter of the tube, means

connecting the pistons together for simultaneous movement including an elongate electrically nonconductive rod having a portion of substantial length slidably confined throughout the length of said tube for reinforcement and means connecting opposite ends of the rod respectively to the pistons, and fluid sealing rings around the rod for preventing leakage of fluid from the cylinders to the tube.
